SHEET FEED RETARDING MECHANISM
FOR PRINTING PRESSESWilliam K. Eckhard, Westerly, R. I., assignor to
C. B. Cottrell & Sons Company, Westerly, R. I.,
a corporation of Delaware

Application June 28, 1935, Serial No. 28,815

4 Claims. (Cl. 271—46)

In sheet feed printing presses where a single mechanism has been used for retarding the travel of the sheets from the feeder to the front sheet register or stop it has been found difficult to 5 sufficiently retard the travel of the sheets and deliver them in a normal flat condition because of the high speed of the feeder and the desirability of bringing the sheets down to a standstill at the front sheet register before the sheets 10 are taken by the sheet taking means.

The object of my invention is to obviate this difficulty by providing two coacting sheet straightening and retarding mechanisms located between the feeder and the front sheet register, 15 the first sheet straightening and retarding mechanism operating to receive the sheets from the feeder at one speed, straighten them, and to transfer the sheets to the second sheet straightening and retarding mechanism at a slower 20 speed, the said second sheet straightening and retarding mechanism operating to still further retard the travel of the sheets on their way to the front sheet register.

My invention more particularly comprises 25 means for feeding sheets to the sheet register at progressively lesser speeds, comprising a sheet feeder adapted to feed the sheets at a faster speed than the surface speed of the sheet taking means, the first sheet straightening and retarding mechanism including an endless chain carrier traveling at variable speeds and having gages 30 adapted to be engaged by the leading edges of the sheets as they are advanced by the feeder while the endless chain carrier is traveling at 35 a higher speed, and the second sheet straightening and retarding mechanism including a reciprocating carrier having gages pivoted thereto, adapted to be engaged by the leading edges of the sheets as the endless chain carrier is traveling 40 at a lesser speed.

A practical embodiment of my invention is represented in the accompanying drawings, in which

Fig. 1 represents in detail top plan so much of 45 a sheet fed rotary printing press and its feeding mechanism as includes my invention, the parts being in the positions they assume when the swinging gages of the second sheet straightening and retarding mechanism;

Fig. 2 represents a side view of the same;

Fig. 3 represents a detail side elevation showing the parts in the positions they assume as the swinging gages of the second sheet straightening and retarding mechanism leave the sheet 50 with its leading edge engaged by the front sheet

register in position to be taken by the grippers of the sheet taking means;

Fig. 4 represents a detail side view of the means for operating the front sheet register;

Fig. 5 represents a detail enlarged top plan 5 view showing the relative positions of the gages on the first and second sheet straightening and retarding mechanisms as the control of the sheets is about to be taken by the swinging gages of the second sheet straightening and retarding 10 mechanism;

Fig. 6 represents a side view of the same;

Fig. 7 represents a detail side view of the second sheet retarding mechanism with the parts 15 in the positions they assume when the swinging gages have dropped down out of the sheet path; and

Fig. 8 represents a similar view with the parts 20 in the positions they assume as the gages are about to be swung upwardly into position to receive the leading edge of a sheet from the gages 25 of the first sheet straightening and retarding mechanism.

The sheet taking means is herein represented 30 as an impression cylinder 1, its shaft being denoted by 2, which cylinder is driven at a predetermined surface speed. The tumbler actuated grippers 3 on the cylinder 1 may be operated in the usual manner by the tumbler cam 4 and its coacting pin 5, to take a sheet from the front 35 sheet register at the proper time; the pin for actuating the tumbler cam for delivering the sheet not being shown herein as it forms no part of the present invention.

The front sheet register may be of any well 35 known or approved construction. In the form herein shown the front sheet stops 6 are carried by the spring pressed rock lever 7, which lever is in turn operated by the spring pressed rock lever 8 which carries a stud or roller 9 contacted by 40 the cam 10 on the cylinder shaft 2, to swing the front sheet stops 6 downwardly out of engagement with the leading edge of the sheet as it is grasped by the cylinder grippers 3. It is obvious that two or more of these front sheet stops 45 are provided to properly front register the sheet before it is taken by the cylinder grippers.

The means which I have shown for feeding the sheets at successively reduced speeds to the front sheet stops 6 is constructed, arranged and operated as follows:

The inner end of the endless tape carrier of the sheet feeder is shown, which tape carrier is arranged to feed the sheets at a speed faster than the surface speed of the cylinder 1. These tapes 55

11 of the endless tape carrier pass around the pulleys 12 carried by the cross shaft 13 at the inner end of the carrier.

5 The first sheet straightening and retarding mechanism includes two endless chains 14 (one only of which is shown herein) overlapping the endless tape carrier in substantially the plane of the sheet path, which chains are driven at varying speeds. These endless chains pass around inner 10 and outer sprockets 15 and 16 carried by the stud shafts 17 and 18 respectively. These chains are provided with aligned front sheet gages or hooks 19 arranged in position to receive the leading edge 15 of the sheet at one speed as it is advanced by the sheet feeding tapes 11 and to transfer the leading edge of the sheet to the second sheet straightening and retarding mechanism at a lesser speed.

The second sheet straightening and retarding mechanism includes two carriages 20 (one only of 20 which is shown herein) reciprocating on tracks 21 toward and away from the front sheet register stops 6 in substantially the plane of the sheet path. The said reciprocating carriages 20 are provided with swinging spring pressed front sheet 25 gages or hooks 22 pivoted thereto to be swung into and out of the sheet path. These front gages 22 are adapted to receive the leading edge of the advancing sheet from the gages 19 on the endless chains 14 of the first sheet straightening and retarding mechanism at a surface speed slightly 30 slower than that of the said gages 19 and rapidly retard the travel of the sheet until its leading edge reaches the front sheet register stop 6.

The means for reciprocating each carriage 20 35 of the second sheet straightening and retarding mechanism comprises a rotary cam 23 mounted on the cross shaft 24, the face of which cam is contacted by a stud or roller 25 carried by a spring pressed rock lever 26. This rock lever 26 40 is connected by a rod 27 to another rock lever 28 which in turn is connected by a rod 29 to the carriage 20. It will be understood that the face of the cam 23 is so shaped that at the time the gages 22 of the second sheet straightening and 45 retarding mechanism receive the leading edge of the advancing sheet from the gages 19 of the first sheet straightening and retarding mechanism the carriages 20 will be traveling slightly slower than the gages 19. Immediately after the 50 gages 22 have received the leading edge of the advancing sheet the carriages 20 are decelerated so that the leading edge of the advancing sheet reaches the front sheet register stop at a greatly reduced speed.

55 The means for swinging each of the gages 22 of the second sheet straightening and retarding mechanism into and out of the sheet path includes a stud or roller 30 carried by the gage, which stud or roller is caused to travel in an endless path by providing a cam groove 31 in each side of the tracks 21, which cam groove opens at its inner and outer ends through the top of the track. These cam groove openings are so arranged that as the carriage 20 reaches the inward 60 limit of its sliding movement the stud or roller 30 will drop into the cam groove 31 and thus swing the gages 22 out of the sheet path. A plate spring 32 located in the cam groove 31 is so positioned and shaped that the stud or roller 30 will force 65 the free end of the spring laterally out of the way on the outward sliding movement of the carriage and will permit the spring to snap back to its normal position as the carriage reaches the limit of its said outward movement. The stud or roller 30 70 will be caused to ride up out of the cam groove on 75

the inclined outer edge of the spring 32 as the carriage is started on its inward sliding movement. This will swing the gages 22 upwardly into the sheet path in position to receive the leading edge of the advancing sheet from the gages 19 on the endless chains of the first sheet straightening and retarding mechanism.

5 The means which I have shown for imparting the variable speed to the endless chains 14 of the first sheet straightening and retarding mechanism is as follows:

An eccentric gear 33 mounted on the cross stud shaft 18 is driven by an eccentric gear 34 mounted on a cross shaft 35. This cross shaft 35 is operatively connected to the cam shaft 24 through the train of gears 36, 37, 38, 39, 40 and 41. The cross shaft 13 for the pulleys 12 at the inner end of the sheet feeding endless tape carrier is operatively connected to the cam shaft 24 through the train of gears 42, 43, 44, 45 and 46. The gear 41 on the cam shaft 24 is operatively connected through the gears 47 and 48 to the gear 49 on the cylinder 1.

From the above description it will be seen that I have provided means whereby the first sheet 25 straightening and retarding mechanism may receive the sheets from the sheet feeder at a certain speed and then rapidly retard the travel of the sheets before transferring them to the control of the second sheet straightening and retarding mechanism; which latter mechanism still further retards the travel of the sheets on their way to the front sheet register.

It will be understood that the sheet feeding mechanism herein shown and described is to be 35 used in connection with the usual side registering and sheet detecting mechanism not shown herein.

It is evident that various changes may be resorted to in the construction, form and arrangement of the several parts without departing from 40 the spirit and scope of my invention, and hence I do not intend to be limited to the particular embodiment herein shown and described, but what I claim is:

1. In a printing press, a front sheet register 45 and means for feeding sheets thereto comprising, a sheet feeder and coacting first and second sheet straightening and retarding mechanisms, the first sheet straightening and retarding mechanism operating to receive the sheet from the feeder at one speed and gradually retard the sheet, and the second sheet straightening and retarding mechanism operating to receive the sheet from the first sheet straightening and retarding mechanism and still further retard the sheet on its way to the front sheet register.

2. In a printing press, a front sheet register and means for feeding sheets thereto comprising, a sheet feeder and coacting first and second sheet straightening and retarding mechanisms traveling in different looped paths, the first sheet straightening and retarding mechanism operating to receive the sheet from the feeder at one speed and gradually retard the sheet, and the second sheet straightening and retarding mechanism operating to receive the sheet from the first sheet straightening and retarding mechanism and still further retard the sheet on its way to the front sheet register.

3. In a printing press, a front sheet register 70 and means for feeding sheets thereto comprising, a sheet feeder and coacting first and second sheet straightening and retarding mechanisms having gages traveling in different looped paths, the gages of the first sheet straightening and retarding 75

mechanism operating to receive the sheet from the feeder at one speed and gradually retard the sheet, and the gages of the second sheet straightening and retarding mechanism operating to receive the sheet from the gages of the first sheet straightening and retarding mechanism and still further retard the sheet on its way to the front sheet register.

4. In a printing press, a front sheet register and means for feeding sheets thereto comprising, a sheet feeder and coacting first and second sheet

straightening and retarding mechanisms, the first mechanism including endless chains having gages for receiving the sheet from the feeder at one speed and for transferring the sheet to the second mechanism at a lesser speed, the said second mechanism including reciprocating carriages having gages traveling in a looped path and operating to still further retard the sheet on its way to the front sheet register. 5
